Elijah P. Penniman, Rochester, New York
Letters Patent (Design) No. 35, dated 9th September 1845

The Schedule referred to in these Letters Patent
and making part of the same:

To all whom it may concern: Be it Known
that I Elijah P. Penniman of Rochester in the County of Monroe,
and State of New York have invented a new plan and Design
for a parlor Stove and I do hereby declare that the following
is a full and exact description of the same. The nature of my
invention is fully represented by Drawings accompanying
A being the Ground Plan showing the form of the sides B and
the ends C and the top represented in figure D. What I claim
as my invention and desire to secure by Letters Patent is the
Ornamental Arrangement and form of the sides, B and ends
C and the Ornamental part of the bottom A as shown by
the Drawings. The Plan of the Top is shown by the dotted
Lines on Figure A.

Witnesses.
